UNITED STATES PATENT OFFICE.

FRANK M. KINNARD, OF SEBRING, OHIO, ASSIGNOR OF ONE-HALF TO CHARLES L. SEBRING, OF SEBRING, OHIO.

BATTER.

Application filed August 4, 1920, Serial No. 401,164. Renewed June 11, 1923.

To all whom it may concern:

Be it known that I, FRANK M. KINNARD, a citizen of the United States, residing at Sebring, in the county of Mahoning and State of Ohio, have invented a new and useful Batter, of which the following is a specification.

This invention relates to batters such as are used in potteries for batteing out clay 10 preparatory to placing the clay in the molds.

The batters such as are at present in general use in potteries are substantially cylindrical in shape and provided with a handle by means of which the bat is grasped in one hand by the batter-out and raised above 15 the block and then brought down with considerable force upon the ball of clay, which has been placed upon the block. These batters are necessarily of considerable weight 20 and it is therefore extremely difficult for the batter-out to continuously swing the batter and maintain it in proper alignment with the block as it is brought down upon the ball of clay. Even the most proficient batters-out cannot produce bats of uniform 25 thickness with the usual form of batter above described.

The objects of the present invention are the provision of a batter mounted upon a 30 lever, a counter-weight being provided upon the lever for the purpose of counter-balancing the weight of the batter, means being provided for adjusting the batter with relation to the lever and to the block and a 35 bumper being provided to limit the downward movement of the batter.

With these objects in view the invention consists in the novel construction and arrangement of parts, hereinafter described, 40 illustrated in the accompanying drawings, and particularly pointed out in the appended claims, it being understood that various changes in the form, proportions, size and minor details of construction may be made 45 within the scope of the appended claims, without departing from the spirit or sacrificing any of the advantages of the invention.

The invention thus set forth in general 50 terms is illustrated in the accompanying drawings forming part hereof, in which—

Figure 1 is a plan view of a batter embodying the invention.

Fig. 2 is a section on the line 2—2, Fig. 1. 55 Fig. 3 is a section on the line 3—3, Fig. 2.

Fig. 4 is a detail perspective view of the adjustable post upon which the lever is pivoted.

A practical embodiment of the invention is disclosed in the accompanying drawings, forming a part of this specification in which similar numerals of reference indicate corresponding parts throughout the several views.

The bench upon which the device is 65 mounted is indicated by the numeral 1 and a casting 2 is fixed thereto and provided with the bearing portions 3 and 4 within which the posts 5 and 6 are mounted.

The post 5 is provided with the beveled 70 faces 7 which conform with the beveled faces 8 of the socket 9 formed in the bearing portion 3 and an elongated vertical slot 10 is formed in said post to receive the bolt 11, the head 12 thereof being received in the 75 opening 13 in the bearing portion and engaging the adjacent face of the post, a nut 14 being provided upon the other extremity of said bolt and engaging the adjacent outer face of the bearing portion 3 in order to 80 draw the beveled faces 7 of the post tightly against the beveled faces 8 of the socket in the bearing portion 3.

The bearing portion 4 is provided with a socket 15 having the beveled faces 16, said 85 socket receiving the post 17, which is provided with beveled faces 18 designed to conform to the beveled faces 16 in the socket. An elongated vertical slot 19 is formed in the post 17 and receives a bolt 20, the head 90 21 thereof being located in a suitable opening 22 formed in the bearing portion 4 and arranged to engage the adjacent face of the post 17, a nut 23 being provided upon the other end of said post and arranged to bear 95 against the adjacent face of the bearing portion 4 in order to draw the beveled faces 18 of the post into tight engagement with the beveled faces 16 of the socket. A block 24 of rubber or the like is mounted in the 100 socket 25 formed at the upper end of the post 17 and acts as a bumper for the lever 26 upon which the batter is carried and which is pivoted at 27 to the upper end of the post 5.

The lever 26 is preferably formed of a pair of spaced angle irons 28, the rear ends thereof being bent upwardly at an angle as shown at 29 and connected to the bar 30 upon which is slidably mounted the weight 110

31, the set screw 32 being provided for adjusting the weight at any desired point upon the bar 30.

The forward ends of the angle irons 28 5 are outwardly flared as shown at 33 and connected by means of the handle 34. The batter 35 is of cylindrical form and is composed of plaster of Paris or the like connected to the base plate 36 by means of the tapered apertures 37 into which the plaster of Paris is embedded.

A pair of uprights 38 is provided upon the base plate 36, said uprights extending between the angle iron portions 28 of the lever.

15 Each of the uprights 38 has a slot 39 formed therein, said slots receiving the squared portions 40 of bolts 41 which bolts extend through both of the angle irons 28. A screw 42 is provided in each of the uprights 38 20 and extends downwardly through the slot therein and engages the upper surface of the adjacent bolt 41 for the purpose of preventing the batter being moved with relation to the lever by the shock of the batter 25 being brought into engagement with the block.

The block 43 is of the usual construction being preferably slightly concaved upon its upper surface as shown at 44 to accommodate the convex lower surface 45 of the batter. The block 43 is mounted upon a pile 46 formed of masonry or the like, located adjacent to the bench 1.

30 With the adjustments provided in the posts 5 and 17 it will be seen that the lever 26 may be adjusted to the desired height to accommodate the batter 35 and the adjustment upon the base plate of the batter provides for adjusting the batter with reference to the lever to compensate for wear 40 upon the batter.

The operation of the device is as follows: Assuming that the counter weight 31 will hold the batter in the raised position above 45 the block 43, a ball of clay is placed upon the block 43 in the usual manner after which the "batter-out" grasps the handle 34 of the lever and pulls the lever down bringing the batter into the position shown 50 in Fig. 2, "batting out" the ball of clay upon the block 43. With the use of this

device the work of the "batter out" is made considerably easier as the counter-weight 31 will counter-balance the weight of the batter 35, thus eliminating the continual lifting of the heavy batter by hand.

55 It will, of course, be understood that for small work such as fruit saucers, individual butter chips and the like, two or three bats may be made with a single operation of the 60 batter. It will be evident from the above description that a batter is provided by means of which considerable of the labor is dispensed with and providing an increased 65 output of work with the minimum effort of the operator.

I claim:

1. In combination with a stationary block, a lever pivoted at one side of the block, a batter mounted upon the lever and arranged 70 to be brought into forceful contact with a ball of clay placed upon the block to produce a bat, a bumper arranged to be engaged by the lever to limit the downward movement thereof and a counter weight arranged to normally hold the lever in the raised position.

2. In combination with a stationary block, a lever pivoted at one side of the block, a batter mounted upon the lever and arranged 80 to be brought into forceful contact with a ball of clay placed upon the block to produce a bat, a bumper arranged to be engaged by the lever to limit the downward movement thereof, means for adjusting the 85 height of the bumper to limit the thickness of the bat and a counter weight arranged to normally hold the lever in raised position.

3. In combination with a stationary block, a lever pivoted at one side of the block, a batter mounted upon the lever and arranged 90 to co-operate with the block, a bumper arranged to be engaged by the lever to limit the downward movement thereof, and a counter-weight arranged to hold the lever 95 in raised position and means for adjusting the batter vertically upon the lever to compensate for wear.

In testimony that I claim the above, I have hereunto subscribed my name.

FRANK M. KINNARD.
